UNITED STATES PATENT OFFICE.

ROBERT W. SCOTT, OF BOSTON, MASSACHUSETTS, ASSIGNOR TO SCOTT AND WILLIAMS INCORPORATED, OF BOSTON, MASSACHUSETTS, A CORPORATION OF MASSACHUSETTS.

STOCKING-KNITTING MACHINE.

1,224,870.

Specification of Letters Patent.

Patented May 1, 1917.

Application filed October 22, 1914. Serial No. 868,108.

To all whom it may concern:

Be it known that I, ROBERT W. SCOTT, a citizen of the United States, and resident of Boston, in the county of Suffolk and State of Massachusetts, have invented certain new and useful Improvements in Stocking-Knitting Machines, of which the following is a specification.

My invention relates to stocking knitting machines, and particularly to circular knitting machines adapted to the production of fabrics having sections side by side of a different texture, such for instance as plain fabric stockings suitable for children's wear having a leg of plain fabric of a comparatively coarse texture, a relatively narrow foot, and a heel, sole and toe, or other desired parts, of a finer texture.

In the accompanying drawings, Figure 1 is a horizontal section through the needle carrier;

Fig. 2 is a plan taken above the web-holder bed, showing the needles in diagram in plan;

Fig. 3 is a detailed vertical section on the line 3—3, Fig. 4, showing the needles, web-holders and means coöperating with said instruments to knit; and

Fig. 4 is a diagram development illustrating typical needle cams and motions of the needles and web-holders with respect to each other.

When producing articles of the desired sort upon stocking knitting machines, it has heretofore been found necessary, in order to obtain a sufficient difference between the coarse fabric and the fine fabric, to provide for the operation of an increased number of needles at the parts of the fabric more closely knit, for instance, by providing for the operation of alternate needles intervening among the others for the finer fabric.

In order to avoid changing the number of needles in operation and for other purposes, including capacity for making the complementary coarse and fine fabric parts of the article automatically of predetermined adjusted relative widths, I provide a needle carrier and needles arranged for knitting one segment of the product with widely

spaced needle wales, and coöperating means for knitting another segment of the fabric of the same texture or of a finer texture, and of a width variable through a wide range at certain times in the production of the article.

Referring now to Fig. 1, the needle carrier 260 may be as shown a grooved needle cylinder adapted for coöperation with the remaining instruments of a suitable circular independent needle knitting machine, for instance such a machine as that described and claimed in my application Serial No. 746,070 filed February 3, 1913 (Letters Patent No. 1,152,850, dated Sept. 7, 1915). A part A of said cylinder carrying needles to knit the front half of the stocking is provided with needle grooves *a* regularly spaced at a certain distance apart, while the remainder B of said cylinder is provided with needle grooves *b* closer together. For instance I may provide 102 grooves *a* and 118 grooves *b*, occupied by 220 needles.

Mounted fixedly upon said needle cylinder, a web-holder bed 295 is provided with a similar number of grooves *w* for independently movable web-holders 290 taking between the needles *n'* occupying the grooves *a* at the front half A of said cylinder, and with a similar number of grooves *w'* for web-holders taking between the needles *n''* at the back half B of said cylinder.

I provide for the web holders at the part B of said cylinder and for coöperation with the more closely spaced needles, means associated therewith for altering the length of the stitch knit at said needles at predetermined times. For instance I may employ the device described and claimed in my application Serial No. 746,070 comprising a movable web-holder cam 312 mounted on web-holder cam ring 301 and capable of being moved through an adjustable distance at predetermined times by the cam 370 and connection 460, to insert said web-holder cam 312, to move in the web-holders when movement of said connection may determine, at an earlier time with respect to the stitch drawing movement given the needles *n''*. For this purpose web-holders 290, 100

associated with needles n^2 may have for contact with cam 312 longer butts than the remaining web-holders, whose butts do not contact with the cam 312. As shown in Fig. 5 4 the normal operation of the needles comprises their advance by the leading stitch cam 7, partial retraction by top center cam 8 to a level between the said top center cam 8 and bottom center cam 9 (at which level 10 said needles take yarn) and a subsequent retraction at stitch cam 6 to draw their stitches, the heads of the needles moving at the line n .

The normal movement of the web-holders 15 290, (arbitrarily shown for clearness in the same plane as the needle movement) causes their hooks to travel as shown at the full line 292, but when the cam 312 is operated by the connection 460 the web-holders having longer butts move inward at an adjustable earlier time on the dotted line 293, thus inserting their hooked portion between the needles at an earlier time with respect to their down-going movement at cam 6, to determine a longer stitch. 25

While I have illustrated said specific means for the adjustable local elongation of the stitches at the needles n^2 , it will be understood that my invention is independent of said specific means and I may employ any other known or usual means for locally varying the length of the stitch at said closely spaced needles. 30

In operation the parts of the stocking requiring to be knit of a coarser texture are knit upon needles n' , n^2 , the web-holders 290 having longer butts associated with the needles n^2 being operated to draw at said needles n^2 stitches so long as to produce the 40 same texture or a nearly similar texture as at the more widely spaced needles n' .

Said needles n' may be the longer butt needles employed for the instep and top of the foot or any other segment of the needles, and the heel, toe and sole of the stocking may be knit upon all of the needles n^2 , or the remainder of the series of needles, the web-holders being adjusted for heel and toe knitting to their normal position, to 45 draw the normal length of loops. Owing to the wide variation in stitch length obtainable by means of cam 312, the sole, heel and toe may be knit on needles n^2 of close fabric of any desired predetermined relative width. The operation may include knitting a leg on needles n' n^2 having a texture rendered uniform by inserting the web-holders at needles n^2 in the described manner, then knitting a finer textured section 50 above the ankle by adjusting the web-holders to insert them at needles n^2 at a later time, needles n' continuing to make coarse fabric; then knitting a heel on needles n^2 at a later time.

25 dles n^2 as usual, and then knitting a foot having coarse fabric at needles n' and 65 fabric at needles n^2 of the closer texture permitted by the closer spacing of said needles n^2 , and then knitting a toe as usual on needles n^2 .

The machine may be equipped with the 70 usual devices (not shown) for elevating and lowering needle cylinder 260, the attached web-holder bed 295 and the web-holders with respect to the knitting cams to vary or determine the length of the stitch 75 at all of the needles, and with yarn-changing and yarn-splicing devices, such as the device F for said purposes fully shown and described in my said application.

The machine may also be provided with 80 any known or usual devices, such as those of my said application (not shown) for knitting heels and toes at the needles n^2 .

What I claim is:

1. In a stocking knitting machine, the 85 combination with needles and means co-operating with a segment thereof to knit heels and toes, of a needle carrier holding for co-operation with said knitting means the needles of said segment in more closely 90 spaced relation than the remaining needles.

2. In a knitting machine a needle carrier, independently movable needles therein spaced more closely at one part than at another part thereof, and means for knitting 95 at all of said needles, in combination with means acting at predetermined times to adjust the stitch length at said closely spaced needles only.

3. In a knitting machine, a needle carrier 100 having needle grooves therein spaced more closely at one part than at another part thereof, independently movable needles in said grooves, and automatic means co-operating with all of said needles at times to knit 105 fabric of like texture at all part of said carrier, and at times to knit of different texture at the differently spaced needles.

4. In a knitting machine, a needle carrier having needle grooves therein spaced more 110 closely at one part than at another part thereof, needles in said grooves, means for knitting at all of said needles and means co-operating with said closely spaced needles to knit fabric of fine or of coarse texture at 115 predetermined times.

5. In a knitting machine a needle carrier and needles therein spaced apart for coarse-textured knitting, another series of needles in said carrier spaced for finer-textured 120 knitting, web-holders, and means co-operating with said web-holders to cause said last mentioned needles to knit coarse-textured and finer-textured web at predetermined times.

6. In a knitting machine, in combination,

a needle cylinder and a web-holder bed respectively having grooves for movable needles and for web-holders, the said grooves being more closely spaced on one side of a substantially central plane than at the other side thereof.

In testimony whereof, I have signed my

name to this specification in the presence of two subscribing witnesses.

ROBERT W. SCOTT.
